AUXILIARY EVAPORATING COIL FOR
THE ICE-MAKING SECTION OF RE-
FRIGERATORSJohn Plumeri, Trenton, N. J., assignor to Kramer
Trenton Company, Trenton, N. J., a corpora-
tion of New Jersey

Application January 27, 1948, Serial No. 4,644

4 Claims. (Cl. 62—126)

1

This invention relates to refrigerating equipment and, more particularly, to an auxiliary evaporating coil for the ice making section of refrigerators, and has for an object to provide such an evaporating coil which is adapted to embrace three sides, including the back side, of the ice making section.

Another object is to provide such a coil which is so constructed as to establish a continuous channel for the circulation of the refrigerant therethrough.

Another object is to provide such a coil which is substantially U-shaped and in which the tube or conduit carries fins at its substantially ninety degree curved corners as well as along its straight portions or runs.

Another object is to provide such a coil which is simpler and more economical to produce and install than a plurality of independent coils.

Another object is to provide such a coil which is, in effect, three coils in one, but which does not require means for interconnecting independent or distinct coil units during installation.

Another object is to provide such a coil which has a notably greater refrigerating effect than three independent coils each of substantially one third its size.

Another object is to provide such a coil which takes advantage and makes use of the vacant space that customarily exists behind the ice making section of refrigerators of standard or usual types.

Another object is to provide such a coil which has improved means for attaching it to an ice making section.

A further object is to provide certain improvements in the form, construction, and arrangement of the several parts, whereby the above named and other objects may be effectively attained.

A practical embodiment of the invention is shown in the accompanying drawing, in which

Fig. 1 represents a front elevation of the new evaporating coil;

Fig. 2 represents a top plan view thereof as associated with an ice making section, the latter being shown in broken lines;

Fig. 3 represents a side elevation thereof; and

Fig. 4 represents a section taken in the plane of the line IV—IV of Fig. 1, looking in the direction of the arrows.

In certain types of refrigerating equipment there is included an ice making section which not only produces the frozen cubes but also, through radiation from its walls and its trays, serves to

2

chill the air within the main storage chamber of the refrigerator. While these functions are generally performed to satisfaction in the case of domestic equipment, it has been found that, in commercial installations, the refrigerator is subjected to such heavy use that the ice maker is not adequate to the load placed upon it and the air within the storage chamber is not sufficiently cooled. A good illustration of this is the reach-in refrigerator which is opened with great frequency and, moreover, is often located in the kitchen of a restaurant.

To obviate this difficulty resort has been had to the provision of an auxiliary evaporating coil which is secured at one side of the ice making section. This auxiliary unit is commonly known as a "booster" coil and, in some cases, two are secured to the ice maker, one at each side. While this practice has improved the functioning of the equipment, it has also entailed disadvantages chiefly with respect to manufacturing and installation expense. Each auxiliary or booster evaporating coil is a complete and distinct unit produced as such and attached as such to the ice making section; each unit having its own return bends on its tube or conduit, and requiring to be coupled in series with the coil of the ice maker and with the other booster coil, when two have been used, in order to provide a continuous circulation path for the refrigerant.

The present invention solves the previously existing problem, eliminates to a large extent the disadvantages attendant upon earlier attempts at its solution, and greatly increases the effectiveness and efficiency of the equipment.

Turning now to the embodiment of the invention shown in the accompanying drawings, the coil includes a tube or conduit denoted generally by 1, which may be composed of suitable metal such as copper, brass or aluminum and consists of several (five in the present instance) superposed portions or runs 2, 3, 4, 5, 6, with their ends connected by bends 7, 8, 9, 10, in order to provide a continuous path or channel, having an inlet 11 and an outlet 12, for the flow of refrigerant. The said bends may be unitary with the tube or may consist of separate pieces suitably secured to the straight runs as by threading, brazing, soldering, etc., all as is well understood in this industry.

The tube or conduit 1 is bent into U-form, as is well shown in Fig. 2, which step may be performed, in any one of several ways known to operatives in this field, on each of the portions 2, 3, 4, 5, 6, individually if they are to be fitted

with separate bends 7, 8, 9, 10; or on a unitary tube as a whole after it has been formed into a superposed series of runs lying in the same vertical plane; and each end of the U is provided with a header plate 13, 14, preferably composed of suitable sheet metal, which headers have holes 15 formed therethrough to receive the runs of the tube and are fixed to the latter, as by soldering.

Operatively associated with the tube or conduit are a multiplicity of fins 16 which, as is customary, may be stamped from thin sheet copper, aluminum, or brass, and be secured in close thermal contact with the tube by expansion of the latter and soldering, or other equivalent procedure. It will be observed that fins are positioned on the curved corners of the tube, as well shown in Fig. 2, thereby taking advantage of the full length of the runs of the tube which is permitted because they are unitary from end to end. The fins may be provided with any suitable or approved means for spacing them substantially uniformly on the tube, several forms of such means being well known in this industry, and no such means being herein shown as it constitutes no part of the present invention. The peripheral shape of the fins is also optional, but I have found it desirable to make them substantially square and of such size that those on each run of the tube abut or approximately abut those on adjacent runs.

The U-shape of the auxiliary booster coil as a whole fits it to embrace three sides of a normal or standard ice making section of a refrigerator, as illustrated in Fig. 2, where the ice making section is conventionally represented in broken lines and denoted generally by 17; the association of the parts being such as to leave the front part or face of the ice making section accessible for insertion and removal of the ice trays, two of which are shown in broken lines and marked 18, 18. Hangers 19, 19, are secured to the ice making section 17 in any appropriate manner, such as by soldering or brazing or riveting them to two sides or the top thereof, the former positioning being shown in the drawing, and their upper ends may be bent, as well shown in Fig. 1, where the hangers are represented as broken to save drawing space, for the purpose of suspending the ice making unit from the top wall of the refrigerator by screws or the like passing through holes 20 formed in the said bent upper ends. The header plates 13, 14, are formed with inner flanges 21, 22, for fastening the auxiliary or booster coil to the ice making section by securing the said header plates directly thereto or, as shown in the drawing, to the hangers 19, 19, which may be accomplished by screws 23 passing through holes in said flanges, or in any other approved manner; the fastening screws being preferably distributed at suitable intervals from the upper part to the lower part of the header plates in order to insure rigidity of attachment. The header plates are also provided with outer flanges 24, 24, to stiffen the said parts.

The inlet and outlet 11, 12, of the tube or conduit may be connected with the tube or conduit of the evaporator unit of the ice making section in order to provide a continuous channel or passage for the refrigerant circulating through the system, as will be so well understood by those familiar with this industry as to call for neither illustration nor further description; or, if it should be so desired under any particular cir-

cumstances, the said inlet and outlet of the tube of the auxiliary or booster unit may be connected to a separate source of refrigerant circulation.

If, in the construction of this unit the bends 7, 8, 9, 10, are formed separately, they may be attached to the ends of the tube runs after the header plates 13, 14, and of course, the fins have been positioned on the tube with the latter passing through the round holes in the header plates and fins shown in the drawings. But, in cases where the said bends constitute integral parts of the tube, the header plates and fins will need to be provided with apertures of such size and shape as to permit the passage of the bends therethrough during assembly of the parts.

From the foregoing description, taken in connection with the drawings, it will be observed that this invention provides, in a single structure, auxiliary evaporating surface area equivalent to that which would be supplied by three separate coils secured to three sides of the ice making section or unit and, indeed, the effective area of this auxiliary coil exceeds that of three such separate coils because it embodies tube portions carrying fins at their curved corners, the bends which would be positioned at these points in the case of separate coils being eliminated in the present structure.

Again, there is a substantial economy in the cost of producing the subject matter of this invention as compared with three separate coils, or even two separate coils, because the expense of giving its U-shaped form to this unitary structure is substantially less than that of manufacturing even two complete separate coils. Furthermore, the mounting of this coil on the ice making unit is a simpler and less expensive procedure than the mounting of two or three individual coils thereon; and such mounting involves no requirement of establishing an interconnection between two or three separate auxiliary or booster coils. As there is generally, if not invariably, waste room or space at the back side of the ice making unit in refrigerators, that portion of the U-shaped coil forming the subject matter of this invention which lies along the back side does not occupy any valuable or otherwise useful space within the refrigerator. This, in sum, it may be said that this invention provides a single unit with greatly increased capacity or effectiveness as compared with previous arrangements of auxiliary or booster coils; and that there is also achieved greater economy, rigidity and simplicity in the manufacture and mounting or association of the parts; while the coil is readily adapted to use in standard and approved kinds of refrigerators without the necessity of redesigning or rearranging the essential parts. While the U-shape herein shown and described lends itself to the fullest attainment of the objects of this invention, an L-shape which is fitted to embrace only two sides, including the back side, of the ice making section may be adopted with results constituting a substantial advantage over previous practices.

In the claims the word "sides" is used in its broad sense so as to include the back side of the ice making section.

It will be understood that various changes may be resorted to in the form, construction, material and arrangement of the several parts without departing from the spirit or scope of the invention; and hence I do not intend to be limited to details herein shown or described ex-

cept as the same may be included in the claims or be required by disclosures of the prior art.

What I claim is:

1. In combination, an ice making section of a refrigerator and an evaporating unit embracing at least two sides of said section, said evaporating unit embodying a plurality of angular shaped tube portions connected at their ends to establish a continuous channel for the flow of refrigerant, header plates secured to the ends of said tube portions, and means attaching the header plates to the said ice making section.

2. In combination, an ice making section of a refrigerator and an evaporating unit embracing three sides of said section, said evaporating unit embodying a plurality of substantially U-shaped tube portions connected at their ends to establish a continuous channel for the flow of refrigerant, header plates secured to the ends of said tube portions, and means attaching the header plates to the said ice making section.

3. In combination, an ice making section of a refrigerator and an evaporating unit embracing three sides of said section, said evaporating unit embodying a plurality of substantially U-shaped tube portions connected at their ends to establish a continuous channel for the flow of refrigerant, hangers for supporting the said section fastened thereto, header plates secured to the ends of said tube portions, and means attaching the header plates to the said hangers.

5 4. In combination, an ice making section of a refrigerator and an evaporating unit embracing three sides of said section, said evaporating unit embodying a plurality of substantially U-shaped tube portions connected at their ends to establish a continuous channel for the flow of refrigerant, vertically elongated header plates secured to the ends of said tube portions, vertically elongated flanges on said header plates, and means for attaching said flanges to the ice making section for assembling the combination.

10 JOHN PLUMERI.
